CLAIM

The ornamental design for a suspended cylindrical luminaire with sound dampening, as shown and described.

DESCRIPTION

FIG. 1 is a top perspective view of a suspended cylindrical luminaire with sound dampening, showing our new design; FIG. 2 is a bottom perspective view thereof; FIG. 3 is a top plan view thereof; FIG. 4 is a bottom view thereof;

FIG. 5 is a front elevation view thereof, the back elevation view being the mirror image of the front elevation view; and, FIG. 6 is a right side elevation view thereof, the left side elevation view thereof being the mirror image of the right side elevation view.

The broken lines shown in the figures illustrate portions of the suspended cylindrical luminaire with sound dampening that form no part of the claimed design.
